(57) **CLAIM**

The ornamental design for a charging station, as shown and described.

DESCRIPTION

FIG. 1 is a top perspective view of a charging station showing the new design.

FIG. 2 is a left side view of the charging station in FIG. 1.

FIG. 3 is a right side view of the charging station in FIG. 1.

FIG. 4 is a back view of the charging station in FIG. 1.

FIG. 5 is a front view of the charging station in FIG. 1.

FIG. 6 is a top view of the charging station in FIG. 1.

FIG. 7 is a bottom view of the charging station in FIG. 1.

FIG. 8 is a bottom perspective view of the charging station in FIG. 1; and,

FIG. 9 is a cross-sectional view of the charging station in FIG. 1.

The dash-dash broken lines illustrate portions of the charging station that form no part of the claimed design. The dash-dot broken lines illustrate the boundaries of the charging station and form no part of the claimed design.

1 Claim, 7 Drawing Sheets
